UNITED STATES PATENT OFFICE.

JOHN HERROLD, OF NEW YORK, N. Y.

COMBINATION TRAY AND GLASS HOLDER.

1,033,052.

Specification of Letters Patent. Patented July 16, 1912.

Application filed September 27, 1911. Serial No. 651,488.

To all whom it may concern:

Be it known that I, JOHN HERROLD, a citizen of the United States, and a resident of the city of New York, Richmond Hill, 5 borough of Queens, in the county of Queens and State of New York, have invented a new and Improved Combination Tray and Glass Holder, of which the following is a full, clear, and exact description.

10 The object of the invention is to provide a new and improved combination tray and glass holder for use in saloons, clubs, private houses and other places, and arranged for convenient attachment to a table or other 15 support to conveniently hold a drinking glass and support cigars, cigarettes, ashes and matches.

For the purpose mentioned, use is made 20 of a standard provided with attaching means for fastening the device to a table or other support, a sleeve mounted to turn on the said standard and provided with horizontal arms standing at an angle one to the other, one of the arms being adapted to support a 25 drinking glass and the other arm carrying an ash tray and match box holder.

A practical embodiment of the invention 30 is represented in the accompanying drawings forming a part of this specification in which similar characters of reference indicate corresponding parts in all the views.

Figure 1 is a side elevation of the combination tray and glass holder attached to a 35 table top to extend below the same; Fig. 2 is a plan view of the same; Fig. 3 is a transverse section of the same on the line 3—3 of Fig. 2; Fig. 4 is a side elevation of the combination tray and glass holder attached to a table and extending above the same.

40 The standard A is provided at one end with a clamp B for attaching the combination tray and glass holder to a table C or other support, the clamp B being provided with a clamping screw D for engagement

45 with the under side of the table C to removably fasten the clamp B in place on the table C. The upper member of the clamp B is preferably provided at the under side with cushioning lugs E, of rubber or other suitable material adapted to engage the top of

50 the table C so as not to mar the table on using the device. The standard A is provided with a reduced portion A' on which is mounted to turn a sleeve F provided with

55 two horizontal arms G and H, provided with receptacle supports, and extending at

an angle one to the other and in different planes as will be readily understood by reference to the drawings. For purposes of illustration, I have shown the arm G having 60 its free end enlarged and apertured for supporting a drinking glass, cup or other vessel, and the said arm provided with spring arms G' adapted to clampingly engage the sides of the vessel so as to securely hold the same 65 in position on the arm G at the same time permitting convenient removal of the vessel whenever it is desired to use the same for drinking purposes. I have also shown the arm H provided with a receptacle support 70 in the form of a tray J.

As shown in Fig. 1, the clamp B is arranged on the upper end of the standard A, so that the standard, the sleeve F and the receptacle supporting arms G and H and 75 the parts carried thereby are below the top of the table C, but, if desired, the clamp B may be on the lower end of the standard A, as shown in Fig. 4, to support the receptacle-supporting arms above the table top. In 80 either case, the sleeve F can be readily turned so as to bring either the glass supporting arm G or the tray supporting arm H into convenient position for the user, it being understood that on turning the sleeve 85 F the parts can be readily moved into an out of the way position until it is desired to use the same.

By reference to Fig. 2 it will be noticed 90 that the arms G and H stand at an obtuse angle one relative to the other, so that the glass carried by the arm G and the tray carried by the arm H do not interfere one with the other and permit their convenient use individually, and both the glass and the 95 tray can be swung under the table to be completely out of the way, or the sleeve F may be turned to move either glass or tray into an outer position to one side of the table for convenient use.

In order to prevent accidental turning of the sleeve F, the arms G, H and the parts supported thereby, use is made of a spring N coiled on the reduced portion A' of the standard A and bearing against the sleeve 105 F so as to hold the same against accidental turning.

Having thus described my invention, I claim as new and desire to secure by Letters Patent:

1. A device of the character described, comprising a standard having one end re-

- duced and provided at its other end with a clamp for detachably securing it to a table or the like, a sleeve mounted to turn on the reduced end of the standard and having in-
5 tegral arms provided with receptacle supports, said arms being arranged with their longitudinal axes placed at such an angle as to bring one side of said supports adjacent to each other, so that the sleeve may be 10 rotated to bring both receptacle-supports simultaneously into alinement with the table or simultaneously out of alinement with the table, or respectively into and out of alinement with the table.
15 2. A device of the character described, comprising a standard having one end reduced and provided at its other end with a clamp for detachably securing it to a table or the like, a sleeve mounted to turn on the reduced end of the standard and having in-

tegral arms provided with receptacle supports, said supports being displaced vertically with respect to each other and said arms being arranged with their longitudinal axes placed at such an angle as to bring one 25 side of said supports adjacent to each other, so that the sleeve may be rotated to bring both receptacle-supports simultaneously into alinement with the table or simultaneously out of alinement with the table, or respectively into and out of alinement with the table.

In testimony whereof I have signed my name to this specification in the presence of two subscribing witnesses.

JOHN HERROLD.
